UNITED STATES PATENT OFFICE.

MINNETTE H. ENLOW, OF BLOOMINGTON, ILLINOIS.

CURTAIN-HANGER.

1,195,797.

Specification of Letters Patent. Patented Aug. 22, 1916.

Application filed September 26, 1914. Serial No. 863,672.

To all whom it may concern:

Be it known that I, MINNETTE H. ENLOW, a citizen of the United States, residing at Bloomington, in the county of McLean and 5 State of Illinois, have invented new and useful Improvements in Curtain-Hangers, of which the following is a specification.

This invention relates to curtain hangers and the principal object of the invention is 10 to provide a simple and efficient device for hanging curtains which is so constructed that the curtains may be conveniently turned to an out of the way position for ventilating or so that the windows may be 15 conveniently washed.

Another object of the invention is to provide a device of this character consisting essentially of two curtain rods extending in opposite directions on either side of the 20 window toward the center and hinged upon brackets so as to permit of their being turned to an out of the way position without the curtains blowing all around and becoming mussed up.

25 Still another object of the invention is to provide a curtain hanger of this character in which the rods are held in proper position or in any out of the way position positively so that the curtain rods cannot be 30 moved accidentally.

A still further object of the invention is to properly support the free ends of the curtain rods where heavy curtains are used or where the curtains are liable to be pulled 35 upon by children.

Further objects of the invention will appear as the following description is read in connection with the accompanying drawing, which forms a part of this application, 40 and in which:—

Figure 1 is an elevation of a window showing the invention applied thereto with one of the curtain rods extending away from the window in a position for ventilating or for washing that side of the window. Fig. 2 is a top plan view. Fig. 3 is a side elevation. Fig. 4 is a detail horizontal section.

Referring more particularly to the drawing, 1 represents an ordinary window frame which has secured thereto adjacent opposite sides the bracket arms 2 each having at their outer or free ends the parallel ears 3 across which extends a pivotal pin or rivet 4. Pivotaly mounted upon this pin is a head 5 having a hollow extension 6 in

which the curtain rod 7 is removably secured by means of a set screw 8. This curtain rod is preferably provided with an ornamental head at its free terminal and is 60 usually constructed of brass tubing or other similar material.

Secured to the wall 15 of the bracket arms 2 and disposed between the parallel ears 3 is a flat spring 11. This spring embodies an attaching portion 16 having one of its terminals offset laterally to provide a guard extension 12, which prevents the curtain from becoming caught between the head and the spring as will be readily understood. The attaching portion 16 of the spring at its opposite end is bent parallel with the guard 12 and thence downwardly and forwardly of the attaching portion 16, and in spaced parallel relation thereto to 75 provide a locking portion 17, the said locking portion 17 being formed on the free terminal thereof with a V-shaped keeper 10 adapted to alternately engage with a plurality of notches 9 formed in the head 5 of 80 the hollow extension. These bracket arms and their associated curtain poles are identical at each side of the window and are each adapted to carry one of a pair of curtains, portières or like articles which may if 85 desired extend over the bracket arm to the window frame. If desired, the tubular extension 6 of each head may have secured thereto a drapery hanger 13 such as is shown in dotted lines in Fig. 2 and there 90 may be secured to the frame beneath the free terminals of the curtain poles a bracket 14 which will prevent the curtain poles from becoming bent where they are comparatively long to extend across wide windows or where they are subjected to heavy 95 pulls by children.

What is claimed is:—

A curtain holder comprising a pair of brackets adapted to be secured to opposite 100 sides of a window frame and each provided at their free ends with integrally formed spaced parallel ears, socket heads pivotally mounted between the ears and having notches therein, a flat spring secured to the 105 forward end of the bracket and disposed in horizontal relation therewith and defined between the ears of each of said brackets, said springs having an attaching portion, one end of the attaching portion of said 110 spring being bent angularly to provide a V-shaped keeper lying in a horizontal plane

with relation to said brackets and adapted
to engage with the notches of the head, and
a guard formed at the opposite end of the
attaching portion of the spring and ex-
5 tending angularly with respect to the
keeper and defined between and longitudi-
nally of the ears at a point flush with one
side each thereof for preventing the curtains

from entering between the heads and
springs.

In testimony whereof I affix my signa-
ture in presence of two witnesses.

MINNETTE H. ENLOW.
